UNITED STATES PATENT OFFICE.

EZRA S. TAYLOR AND WILLIAM H. MUSSEY, OF CHICAGO, ILLINOIS, ASSIGNEES TO THE PULLMAN COMPANY, OF CHICAGO, ILLINOIS, A CORPORATION OF ILLINOIS.

DRINKING-CUP DISPENSER.

Application filed April 28, 1922. Serial No. 557,103.

The invention relates generally to dispensing mechanisms, and is particularly concerned with devices for housing and dispensing collapsed paper drinking cups.

5 The principal purpose of the invention resides in the provision of an improved cup dispenser peculiarly adaptable for installation in such locations as the narrow offset end-corridors of Pullman railway cars when 10 economy of space and the directions of both manipulation and discharge of the dispenser are the controlling factors in gauging the desirability of the device for its employment in such locations.

15 While the foregoing statement is indicative of the nature of the invention, other objects and advantages not herein specifically referred to will be appreciated upon a full comprehension of the novel features 20 of the dispensing structure.

In order that the invention may be readily understood, a preferred embodiment of the same is set forth in the accompanying drawings and in the following detailed description 25 based thereon. Obviously the invention is susceptible of embodiment in other and varied constructional forms without departure from the essence of the invention or the sacrifice of its material advantages; 30 wherefore it is to be understood that the drawings and description are to be taken in an illustrative and not in an unnecessarily limiting sense.

In the drawings

35 Fig. 1 is a side elevation of the dispenser; Fig. 2 is a vertical section on the line 2—2 of Fig. 1; Fig. 3 is a horizontal section on the line 3—3 of Fig. 2; 40 Fig. 4 is a similar section on the line 4—4 of Fig. 2; Fig. 5 is a similar section on the line 5—5 of Fig. 2; Fig. 6 is a fragmentary vertical section 45 on the line 6—6 of Fig. 2; and Fig. 7 is a similar section on the line 7—7 of Fig. 3.

Referring now in more detail to the drawings, it will be observed that the outer casing 10 of the dispenser comprises a vertically positioned metal tube 11 of substantially elongated rectangular cross-section which is closed at its upper end by a cap 12 and at its lower end by a cap 13. The casing is 55 provided, at a short distance above the cap

13, with a horizontal false bottom 14 upon which a vertical stack of the collapsed drinking cups 15 are supported.

Above this false bottom one of the relatively narrow side walls of the casing is 60 equipped with a door 16 occupying the major portion of said wall, and the opposite side wall is equipped with a narrow vertical sight glass 17. The door, which is hinged along its bottom and locked at its top, 65 gives access to the casing for replenishing the supply of cups therein; and the sight glass permits, without the necessity of unlocking and opening the door, an inspection at any time to determine the number of cups 70 yet stacked therein.

The relatively wide front and rear walls of the casing are vertically corrugated from points just above the false bottom 14 to points just below the cap 12 by the formation, in the outer face of each, of preferably two inwardly pressed recesses 18. These recesses—which are shown most clearly in Fig. 3—serve, first, to give added rigidity 75 to the casing; second, to provide space for the means used for attaching the rear wall of the casing flush to the wall 19 of the car passageway; and, third, to provide, on the inside of the casing, two oppositely disposed vertical channels 20 in which the trunnions 21 of a vertically slidable weight member 22 are adapted to move, and resulting ribs 23 on both sides of the guide channels for maintaining the stacked cups in vertical alignment. Inasmuch as the corrugations do not 80 extend down to the false bottom 14 on which the lowermost cup in the stack rests, short vertical weight and cup-guiding strips 24 are introduced, as illustrated in Fig. 4, between the false bottom and the lower ends 85 of the ribs 23 to provide, in effect, downward continuations of the latter.

The means referred to for attaching the casing to the supporting wall preferably 90 consists of two substantially flat hooks 25 which are secured rigidly to the rear wall of the casing in the upper ends of the recesses 18. The free ends of the hooks are offset 95 slightly from the bases of the recesses and are adapted to project downwardly through openings provided for that purpose in substantially flat band clips 26 secured by screws or the like to the supporting wall, the clips being of less width than the recesses 18 in the casing in order that the hooks and clips 100

may be completely contained within the recesses when the casing is properly mounted on the supporting wall with its rear wall held flush, and in approximate peripheral contact, with the same.

The weight member 22 referred to is, aside from the medially projecting trunnions 21, of elongated rectangular shape with an upturned flange about its entire 10 periphery and is adapted to rest upon the top of the uppermost cup 15 in the stack. The purpose of the member 22 is to apply a downward pressure on the stacked cups to insure that the lowermost cup—and particularly the closed end thereof—is resting flatly 15 on the false bottom 14 in proper position to be engaged by the ejector mechanism. That end of the weight member disposed over the closed ends of the cups is provided with a 20 weight 28 for a purpose hereinafter apparent. A handle 29 may be attached to the upper surface of the weight member if desired as a convenient means for lifting that member when inserting a new stack of cups 25 thereunder.

The ejector mechanism will now be described. A horizontal cup slot 30 is provided in the casing flush with the top of the false bottom 14 and in alignment with the 30 closed end of the lowermost cup 15. An ejector plate 31 is reciprocally mounted in the channel of a guide bracket 32 secured to the under side of the false bottom 14, and is provided at one end with an upturned cup- 35 engaging lip 33 which projects through an aperture 34 in the false bottom 14. When the ejector plate 31 is moved toward one side of the casing in the direction of the cup slot 30, the lip 33 is adapted, by abutting 40 against the downwardly facing overlapped and sealed edge 35 of the lowermost cup, to push the cup with its closed end foremost a short distance through the discharge slot 30 at one side of the dispenser. The projecting closed end of the cup may then be 45 grasped between one's fingers and the cup withdrawn from the slot.

While it is highly desirable that the cups be discharged from the dispenser closed end 50 foremost and at a point at one side of the dispenser where a person standing in the narrow passageway in front of and necessarily quite close to the dispenser can conveniently grasp and remove the partially exposed cup, it is also equally desirable that 55 the ejecting mechanism actuating this lateral discharge of the cups be operated by a manual movement toward or away from the person standing in front of the dispenser. 60 In order to accomplish this the ejector slide 31 is provided on its under surface with a downwardly projecting lug 36 which moves in a slot 37 of the guide bracket 32. The lower end of the lug 36 rides in an oblique 65 cam slot 38 formed in a slide 39. This slide

is reciprocally mounted to move horizontally at right angles to the ejector plate in the channel of a guide bracket 40 secured centrally to the front and rear walls of the casing 10 below the guide bracket 32, and is 70 provided with a downwardly projecting finger piece or pull handle 41 which extends through aligned apertures 42 and 43 in the guide bracket 40 and casing cap 13 respectively. When the handle is in its rearward 75 position—in which position it is normally maintained by the action of a coil spring 44—the ejector lip 33 is in its retracted position ready to engage the lowermost cup; and, when the handle 41 is pulled forwardly 80 the ejector lip—through the cam connection of the ejector plate with the slide 39—is moved laterally of the casing toward the cup slot 30 and projects the closed end of the lowermost cup therethrough. 85

We claim:

1. In a device for dispensing drinking cups, a casing adapted to contain a plurality of collapsible cups in superpose relation and provided in one vertical wall with a horizontal slot for the discharge of the lowermost cup, a horizontally reciprocable slide movable toward the slot and provided interiorly of the casing with means for projecting the lowermost cup into the slot, another horizontally reciprocable slide movable transversely of the first mentioned slide and provided exteriorly of the casing with means for moving the same, an oblique cam surface presented by one slide, and a projection presented by the other slide and co-acting with the cam surface for causing movement of one slide upon movement of the other. 95

2. In a device for dispensing drinking 105 cups, a casing adapted to contain a plurality of collapsible cups in superpose relation and provided in one vertical wall with a horizontal slot for the discharge of the lowermost cup, a horizontally reciprocable slide 110 movable toward the slot and provided interiorly of the casing with means for projecting the lowermost cup into the slot, another horizontally reciprocable slide movable transversely of the first mentioned slide 115 and provided exteriorly of the casing with means for moving the same, and a coacting pin and oblique slot connection between the slides for causing movement of the former upon movement of the latter. 120

3. A device for dispensing drinking cups, a casing adapted to contain a plurality of collapsible cups in superposed relation and provided in one vertical wall with a horizontal slot for the discharge of the lowermost cup, means for horizontally projecting the lowermost cup into the slot, and a horizontally reciprocable finger piece connected with the cup feeding means and movable lengthwise of a slot in the bottom of the cas- 125 130

ing at right angles to the direction of feed of the cups for operating the cup feeding means.

4. In a device for dispensing drinking cups, a casing adapted to contain a plurality of collapsible cups in superimposed relation and provided in one vertical wall with a horizontal slot for the discharge of the lowermost cup, a horizontal partition within the casing at the level of the slot for supporting the cups, a horizontally reciprocable ejector plate movable along the under side of the partition and provided with a
- lip projecting upwardly through a slot in the partition to engage with and feed the 15 lowermost cup, a horizontally reciprocable handle movable at right angles to the direction of movement of the ejector plate, and a pin and oblique cam slot connection between the handle and the ejector plate for 20 moving the plate to feed the lowermost cup when the handle is actuated.

In testimony whereof we have hereunto subscribed our names.

EZRA S. TAYLOR.

WILLIAM H. MUSSEY.
